Atlys.*

UNITED STATES PATENT OFFICE.

KENNETH HOWIE, OF NORRISTOWN, PENNSYLVANIA, ASSIGNOR TO WILDMAN MFG. CO., OF NORRISTOWN, PENNSYLVANIA, A CORPORATION OF PENNSYLVANIA.

SPRING-BEARD KNITTING MACHINE.

Application filed January 31, 1927. Serial No. 164,844.

One object of my invention is to provide in a spring needle knitting machine employing individual pressers, means controlled by a notched presser wheel and by adjustable cam means whereby a variety of designs may be formed in the fabric.

Another object of this invention is to provide means for making patterns in the leg of a seamless stocking knit upon a circular machine, such as that known as the Pigeon, which employs spring beard needle, direct fed, and has a presser for each independently operated needle.

Other objects of the invention will appear from the following description.

The invention consists in the features and combination and arrangement of parts hereinafter described and particularly pointed out in the claims.

20 In the accompanying drawings

Fig. 1 is a plan view in the nature of a diagram of a knitting head with my improvement in place.

25 Fig. 2 is a sectional view along line 2—2 of Fig. 1 with parts in elevation.

Fig. 3 is a view of a group of pressers, having their edges, which are to cooperate with presser cams, of different formation for making the pattern.

30 Fig. 4 is a plan view showing the several presser cams which cooperate with the pressers of Fig. 3 and with the tuck wheel for making the pattern.

Fig. 5 is a rear view of the presser cams 35 assembled in a group in working relation to each other.

Fig. 6 is a front edge view of the presser cams.

Fig. 7 is a side view of the presser cams.

40 Fig. 8 is an enlarged view of one of the needle beard pressers.

In these drawings 1 indicates diagrammatically the head of a circular hosiery machine, say of the Pigeon type, though it will be understood that the invention may be applied to spring needle machines of other types. The circular row of needles is indicated at 2. 3 indicates the pressers, there being one of these for each of the independently operated needles throughout the needle row. These pressers are mounted to have rocking movement to bring their edges which press the needle beards into position to be engaged by the needle beards as the latter recede in

order to produce knitting, or if any presser is not moved radially inward into the path of the beard of the descending needle, the said beard will not be closed, the old loop will not be cast off and this needle will produce a tuck stitch at the next round, and it is the order of recurrence of these tuck stitches in relation to the regular knit stitches which produces the pattern in the fabric.

At 4 is shown the presser cam which is usual in machines of this type, for pressing the needle beards on the counter clockwise stroke during reciprocating knitting for making the heel and toe.

At the position 5 which indicates the radial line of the knitting head at which the presser cam is located for round knitting and for the clockwise stroke of the needle circle during reciprocating knitting I locate a tuck presser wheel 6. This is mounted to rotate about the pin 7 in the arm 8 of a bracket 9 which is screwed at 10 to the head of the machine. This tuck wheel is provided with shallow notches 11 and deep notches 12 radially disposed and in the present illustration, which is employed as a showing of one form of the invention which may be used, the said notches alternate with each other. It will be understood, however, that while this tuck wheel will produce one and one tuck, the invention may be carried out with other dispositions of shallow and deep notches in the tuck wheel. This tuck wheel is adapted to press the beards of those needles which, as the needle row revolves, align with the shallow notches in the wheel and come in contact with the edge of the wheel at the bottom of said notches.

The alternate needles which align with the deep notches will not have their beards pressed and consequently tuck stitches will be delivered from these needles.

The pressers are slabbed off at their sides to provide thinned upper ends 13 to enter the notches of the tuck wheel. Associated with this wheel I provide means for eliminating, at times, the tucking action of the tuck wheel, for producing pattern effects. For this purpose the pressers are of different formations as shown in Fig. 3, their outer edges being cut differently. These edges are borne upon by one or the other or others of presser cams 15, 16, 17 arranged in a bank, one above the other but below the notched presser wheel and in the plane of the diameter of said wheel.

These presser cams are supported by the fixed ring 1^a of the knitting head and are movable radially of the said head. They are slotted as at 18, the upper one 15 having a countersink at 19. The ring 1^a has a stud 20 extending up into the slots and a screw 21, having a head fitted to the counter-sink of the upper cam, is seated in the stud. Thus the cam members are held to the ring 1^a, but 5 are permitted the necessary sliding movement to present their cam edges 22 to or withdraw them from the path of movement of the outer edges 14 of the pressers. These cams have their edges 22 adjacent the edge of the notched 10 presser so that when either one or more of the cams is advanced radially inward they will, in effect, close the deep notches in the periphery of the tuck or trick wheel and will, therefore, eliminate its tucking action, by 15 closing the beard of those needles which, except for the presence of the cam, would tuck. 20 The cam slides are arranged in the radial plane of the tuck wheel passing through its axis and the axis of the head. Each cam 25 slide has a downwardly extending two-part arm 23, in which is seated a screw threaded stem 24 which supports a spring 25. This spring bears at one end upon the arm 23 and at its other end upon the arm 26 of a bracket 30 which is fixed by a screw 26^a to the ring 1^a. The tendency of the spring is to force the cam slide radially inward to act upon the pressers and cause them to press the needle beards. The inner ends of the screw stems by coming 35 against the outer face of the ring 1^a limit the inner position of the presser cams. By turning these screw threaded stems, the position of the cams for pressing can be accurately determined. The two parts of the arm 23 can 40 be drawn together by a screw 27 in order to lock the screw threaded stem 24 against turning and affecting the accuracy of the adjustment. 45 The presser cams are retracted against the pressure of the springs 25 by levers pivoted at 28 and having arms 29 to bear on the depending arms 23 of the cam slides. The levers are controlled through any suitable connections extending back to pattern mechanism. I show as an example, arms 30, 31, 32, 50 one for each of the levers 29. When either of these arms is swung leftward, the corresponding lever 29 will be operated and the presser cam belonging to that lever will be held in retracted position so long as the connection remains in the position which effects 55 the retraction of the cam. The arm 30 is fixed to a shaft 30^a having an arm 30^b on one end and an arm 30^c on the other end. These 60 arms may be operated by any suitable pattern mechanism to control the position of the uppermost presser cam slide 15. The arm 31 controls the operation of that lever 29 which 65 controls the intermediate cam slide 16. This arm is fixed to a sleeve 31^a having an arm 31^b

for operation by the pattern controlling means.

Arm 32 controls the lower cam slide 17. This arm is attached to an inner sleeve 32^a having an arm 32^b for operation by suitable 70 pattern means. This arm 32 is also controlled by an angular shaped arm 32^c on a sleeve 32^d provided with an arm 32^e to be operated by suitable controlling means.

This last described mechanism, as above 75 stated, controls the position of the lowest cam slide 17. This presser cam slide is used in cooperation with the presser cam 4, for reciprocating work. It is also controlled for making the pattern in round knitting. These 80 presser cams cooperate with the pressers shown in Fig. 3. These pressers, as before stated, are differently formed to effect pressing and tucking in such manner as prescribed to get the pattern desired. I have 85 shown a group of four pressers. This group is repeated throughout the whole circle of needles. The grouping shown is an arbitrarily selected one and is representative of any selection or grouping that may be desired. 90 In the particular grouping shown, the presser marked *a* has its edge 14 intact throughout so that no matter which of the presser cams 15, 16, 17 is advanced, this presser would be 95 tilted inwardly and would press the beard of the needle with which it is associated. The presser *c* has a notch extending from its upper end part way down its edge 14. If either the upper or the intermediate presser cam 15, 16 is advanced, this presser will not be operated thereby because of the said notch clearing the two uppermost presser cams.

Presser *b* will be operated by the uppermost and lowermost presser cams, but not by the intermediate presser cam, as it has a notch 105 opposite this intermediate cam 16. This cam, in order to enter this notch, has its forward end beveled, as shown in Figs. 4 and 7.

Presser *d* will be operated by the two lowermost presser cams but not by the uppermost 110 presser cam 15 because its notch is in the path of the upper presser cam and its intact or uncut edge is in line with the two lowermost cams.

It now will be understood that if the uppermost presser cam is advanced radially inward to its active position, it will eliminate any tucking action which the notched trick wheel might have had at pressers *a* and *b*, because said upper cam will find an engaging edge 14 on the said pressers, and they will be moved inwardly to press the needle beards, but as to the other two pressers *c* and *d*, of this group of four, these will present cut out portions of their outer edges to this upper presser cam, and hence if the deep notch in the trick wheel matched with these pressers, then the tucking control exerted by the trick wheel will not be nullified, but will take place.

If the intermediate presser cam is advanced, 130

it will operate pressers *a* and *d* to press the needle beards irrespective of the occurrence of deep notches in the tuck wheel, but this cam will not operate pressers *c* and *b*, hence these will be under control of the trick wheel to knit or tuck, as the case may be.

If the lowermost presser cam is advanced, then all of the pressers *a*, *b*, *c*, *d* will be operated to press the needle beards and no tucking would result, but ordinary knitting would be produced all around the fabric. This is because all of the pressers have intact portions in the same horizontal plane, i. e. the plane in which the lowermost presser cam is located. Fig. 3 illustrates this construction of the pressers from which it will be noticed that on each presser the lower portion of the edge 14 is uncut.

This cam is advanced in making the heel and toe, or during reciprocating knitting.

The pressers can be arranged in any desired grouping and follow each other around the circle in any desired order, according to the pattern it is desired to produce in cooperation with the trick wheel having the shallow and deep notches. This trick wheel, as stated, makes one and one tuck. This may be regarded as the basis of the pattern, it being modified by the differently notched pressers and the different presser cams associated with and eliminating the action of the trick wheel according to the prescribed plan. As an example, if the upper presser cam is advanced, knitting would be done wherever pressers *a* and *b* occur in the needle row, because the corresponding needles would have their beards pressed. Pressers *c* and *d* would not be operated by this cam, but these pressers would be acted on by the tuck wheel to press some and tuck with others.

The connections for setting the lowermost cam into operating position can be of any suitable form. This cam will be set in operative position to operate all the pressers when the machine changes to reciprocating knitting for making the heel and toe, also this same cam can be set in operative position for round knitting, and for this purpose the arm 32 will be operated from another source of power on the machine. One source of power would be a suitable pattern chain through the arm 32^a and the connections operated thereby, and the other source would be from a cam operating the connections through the arm 32^b.

It will be understood that I do not limit myself to a group of four distinctive pressers, as a different number may be employed to get a pattern effect. Nor do I limit myself to a one and one tuck wheel, and as an example of a different form of said wheel, I may employ a two and one tuck wheel. Neither do I restrict myself to a bank of three cams, as other numbers of cams may be employed. For instance, if an additional presser or press-

ers having cuts or notches distinguished from those described above are employed, an additional cam or cams will be used. Again, only two cams may be employed, one of these would be employed to operate all the pressers around the needle circle, thus eliminating the action of the tuck wheel for either round or reciprocating knitting, and the other cam, when set in operative position (the first mentioned cam being withdrawn) would operate only a portion of the series of pressers, it missing the rest of the series, which would be cut to present notches to this cam, leaving them under the control of the tuck presser wheel to produce the pattern as prescribed. Further, I do not restrict myself to a series of sliding cams, as a pivoted cam may be used, such as is shown in Letters Patent of the United States, granted to me Feb. 21, 1922, Patent No. 1,407,684.

It will be seen from the above that I provide a hosiery machine capable of producing a pattern during round knitting and for producing plain fabric on the heel and toe, the means for getting these results being located at the point where the presser cam for round knitting ordinarily is mounted on the machine, said cam in the present case being adjustable to and from working position automatically to accord with the prescribed order of knitting and the formation of the leg or foot and toe or heel.

It will be seen from the above that we have first the control exerted by the notched wheel whereby some needles knit and others tuck, and we have, second, the control exerted by reason of the differential notching of the pressers and the cooperation of the cam means with these differently notched pressers, and when this second control (the cam means) is brought into action for the formation of the pattern fabric, the first control, i. e. the notched wheel, is eliminated as to some of the pressers leaving others of the pressers under the control of said wheel.

It may be noted also that the standard hosiery machine has 260 needles in the circle whereas the present machine has 261 needles.

As will be seen by the appended claims, I do not limit myself to hosiery machines as the invention can be applied for instance to body machines.

By having the cams controlled from two sources as referred to above, I can employ a short pattern chain for making the pattern, said short chain being thrown out of action when desired by the main chain of the machine.

With the two ways of controlling the cam means I can use said short pattern chain which keeps repeating itself throughout the portion of the stocking in which the pattern is knit.

When the high spliced heel is reached arm 31^b is moved from the main drum of the ma-

chine causing all the low and medium butt needles to knit plain.

- I do not limit myself to the relative notching of the pressers shown, nor to employing the bottom cam for making plain fabric at the heel. Other orders of notching may be employed and for making plain fabric in some cases it may be desirable to let all three cams be in advanced position.
- 10 It will be understood that, in accordance with ordinary practice, the notches and grooves of the tuck wheel 6 are incommensurate with the number of needles in the needle circle.
- 15 I claim:
1. In combination in a spring beard needle knitting machine, individual pressers for the needle beards, having their cam contacting edges differently formed relative to each other
  - 20 for knitting and tucking, a tuck presser wheel adapted to operate certain of the pressers to knit and having deep notches to permit certain pressers to remain idle for tucking and cam means for eliminating the action of the tuck wheel upon certain of the pressers by operating said certain pressers and missing others, the latter being left under the control of the tuck presser wheel, substantially as described.
  - 25 30 2. In combination in a spring beard needle knitting machine, a series of pressers, individual to the needles thinned at their upper ends and notched in different horizontal planes relative to each other, cam means acting selectively on said pressers to operate some and not others, a presser wheel cooperating with the thinned upper ends of the pressers and notched to miss pressing certain of said pressers, said cam means coacting with the pressers in a plane below the plane of the presser wheel, substantially as described.
  - 35 3. In combination, spring beard needles, pressers individual thereto, differently notched relative to each other, a plurality of sliding cams arranged one above another and cooperating to select certain of said pressers and operate them for pressing the needle beards, and a presser wheel arranged in a plane above said sliding cams and notched to miss operating certain of said pressers and means for operating the sliding cams, said cams sliding in a direction parallel with the diameter of the said wheel, substantially as described.
  - 40 45 50 55 4. A knitting machine according to claim 3 in which the sliding cams are spring pressed into position for operating the pressers, and

means for retracting said cams from operating position.

5. A knitting machine according to claim 60 3 in which the cams are provided with downwardly extending arms, operating means engaging said arms for retracting the pressers and springs for advancing them, substantially as described. 65

6. In combination in a seamless hosiery machine for performing either round or reciprocating knitting, spring beard needles, pressers individual thereto, a presser cam for operating the pressers for reciprocating knitting, said pressers being notched differently relatively to each other, a presser wheel for operating certain of the pressers and notched to miss others, adjustable cam means for selectively operating certain of the pressers, 70 while not operating others because of their notches, means for automatically adjusting the cam means, said presser wheel and cam means being located at the position ordinarily occupied by the presser cam which acts during both round knitting and reciprocating knitting. 75

7. A seamless hosiery machine according to claim 6, in which the adjustable cam means under one adjustment thereof operates all of 80 the pressers for reciprocating knitting. 85

8. A seamless hosiery spring beard needle knitting machine, having a presser for each needle, a cam for operating the pressers during reciprocating knitting, said pressers being notched differently relatively to each other, a notched presser wheel for selectively operating the pressers, and a plurality of 90 slideable cams with operating means therefor for selectively operating the pressers according to the relative disposition of their intact portions and notches, said cam means consisting of a plurality of slideable cams arranged beneath and moving diametrically of the presser wheel, said presser wheel and sliding cams being located in respect to the needle circle at the point usually occupied by the presser cam for round and reciprocating knitting, substantially as described. 95 100

9. A knitting machine according to claim 105 8 in which all of the pressers have intact portions in the same horizontal plane and one of the slideable cams is in the plane of said intact portions to operate all the pressers when said slideable cam is advanced, substantially 110 as described.

In testimony whereof, I affix my signature.

KENNETH HOWIE.
